UNITED STATES PATENT OFFICE.

LEON SCHWARZMANN, OF NEW YORK, N. Y.

AUTOMATIC EMBROIDERING MACHINE.

Application filed November 2, 1921. Serial No. 512,184.

The present invention relates broadly to sewing machines, and more particularly to sewing embroidering machines which are entirely automatic in operation and capable 5 of producing embroidery designs of a most complex and intricate nature with perfect accuracy and efficiency, independently of the skill of the operator. The present machine, due to its entirely automatic operation, is 10 capable of producing any desired number of a given design in exact counterparts. This result is almost impossible with machines guided by hand, as even an experienced operator is apt to produce slight variations 15 and even mistakes.

An important object of the present invention is to provide an entirely automatic feed for the tambour which holds the material being embroidered, so it can be moved in 20 any direction and to any extent within predetermined limits, radially from the needle, to produce a stitch of any desired length within such limits and in any direction.

Another object of the invention is to provide an embroidering machine having pattern controlled feed predetermining mechanism and feeding mechanism, which mechanisms are intermittently in operative engagement to relieve the pattern from the strains 30 of moving the feeding mechanism.

Still another object is to provide means for adjusting at will the length of the stitches irrespective of the direction of feed of the material being embroidered, so that 35 variations in the size of a given design can be produced from the same pattern.

A further object of the invention is to obtain a larger number of stitches from every inch of pattern than has heretofore 40 been possible, whereby the cost of the pattern may be materially reduced.

A still further object of the invention is to provide a continuously driven pattern in intermittent operative engagement with the 45 feed predetermining mechanism to render its working noiseless and insure a greater accuracy in the feeding of the pattern than can be obtained by an intermittently driven pattern such, for example, as a ratchet wheel and pawl.

Still a further object of the invention is to provide spring pressed means insuring constant contact between the teeth of cooperating gears during operation thereof to elim-

inate all back lash of the gears and insure 55 accurate feeding of the cloth being embroidered.

An additional object of the invention is to provide a pattern control which may be in tape, ring or type-like form.

Still another object of the invention is to provide convenient means whereby the cloth-carrying device may be operatively disconnected from the feeding mechanism to permit manual shifting thereof.

Still a further object of the invention is to provide convenient means to put "in figures," or, in other words, to make legible a design which it is desired to automatically and correctly reproduce in embroidery by the 70 machine.

The foregoing and other objects of the present invention, together with their attendant advantages, will be apparent as the invention becomes better understood by reference to the accompanying specification and drawings, forming a part thereof, it being premised that changes may be made in the various details and the manner of operation within the scope of the appended claims, 80 without departing from the spirit of the invention.

In the drawings,—

Figures 21 to 26 are detail views of different forms of pattern wheels;

30 Figure 27 is a plan view of the apparatus for putting "in figures" or making designs;

Figure 28 is a sectional view on the line XXVIII-XXVIII of Figure 27;

35 Figure 29 is a diagrammatic view illustrating the periods of rest and movement of different parts of the machine;

Figure 30 is a diagrammatic view illustrating the movement of the feeding lever;

40 Figure 31 is a developed view of a portion of the pattern;

Figure 32 is a developed view of the cam for operating the feeding lever;

Figures 33 to 38 are detail views of portions of the braking mechanism, illustrating modified forms thereof;

45 Figure 39 is a perspective view of a portion of the feeding mechanism; and

Figures 40 and 41 are detail views illustrating the correction device for the feeding lever.

50 In all of the upper or foot feed, and also the under feed machines, certain kinds of material being embroidered, such as canvas or fine silk, do not lie sufficiently flat over the bed plate during the feeding process and often become wrinkled to such an extent as to impair the operation of the machine. To overcome this, and for other obvious reasons, the present machine employs a tambour or hoop in which the material is conveniently stretched and held in position by an inner ring. The feeding movement is then imparted to the stretched cloth by means of suitable connections with the tambour, as will be explained later.

55 The present invention is not limited in its

application to the specific construction of stitch forming mechanism in connection with which it is represented by the several views, as the drawings are illustrative only and for the purpose of giving a clear understanding of the operation of the invention.

Referring to the drawings, the bed plate

1 of the improved machine supports the usual arm standard 2, in the upper part of which is journaled the main shaft 3 in suitable bearings 4.

One end of the main shaft is provided with the usual driving pulley 5 and flywheel 6, while the other end is connected with any usual needle reciprocating mechanism.

On the main shaft 3 is a bevel gear 7 meshing with a bevel gear 8 on the upper end of a vertical shaft 9 journaled in suitable bearings 10 carried by lugs 12

projecting inwardly from the arm standard 2. At the opposite end of the shaft 9 is secured a bevel gear 14 meshing with a similar gear 15 on the horizontally extending shuttle shaft 16.

The gears 7 and 8 preferably have a gear ratio of two to one, while the gears 14 and 15 have a gear ratio of one to one, so that the shuttle shaft 16 revolves twice for every revolution of the main shaft

3. The shuttle shaft 16 is journaled in suitable bearings 17 carried by the bed plate, and has secured to one end thereof a shuttle

18 which may be of any construction adaptable for machines of this type. The needle cooperates with the shuttle to form the stitch in the well known manner, and will not be described in detail herein, as it forms no

part of the present invention. The tension and take-up devices may also be of any usual or well known construction.

The mechanism for feeding the material to be embroidered is conveniently divided into two parts, namely, the feeding mechanism proper and the pattern controlled mechanism which predetermines the variable movement of the feeding mechanism by

positioning its component parts just before each feeding period in accordance with the pattern. Both of said mechanisms are operative and inoperative alternately, as will be more fully pointed out hereinafter.

The cloth plate 19 of circular disk-like

form, as clearly shown in Figure 2 preferably provided with a nickel-plated upper

surface to facilitate movement of the cloth thereon, has a hole 20 formed therein for the

passage of the needle, and is secured to the bed plate in the recessed portion 21 thereof by pins or screws 22 projecting downwardly

therefrom and secured in position by locking means 23, as clearly shown in Figure 3.

The tambour 25 in which the fabric is stretched and maintained in stretched condition by an inner ring 26, is clamped to a

tambour arc 27 by means of a suitable pin projecting from the tambour and passing through an opening in the center of the

75

95

100

105

110

115

120

125

130

5 tambour arc to receive a knurled nut 28. Cooperating with the pin and knurled nut are side pins 29 projecting inwardly from the tambour arc and engaging openings in the tambour.

10 The tambour arc 27 has two lugs 30, at substantially 90° from the other, to which are connected two arms 31, one loosely by a pivotal connection 32 and the other rigidly by screws or rivets 33. The arms 31, at their opposite ends, are each pivotally connected to an arm 34. The opposite ends of the arms 34 are in turn welded or otherwise secured to two members 36 mounted on the ends of the pivots 37, Figures 4 and 5, protruding upwardly through the bed plate 1 and secured by set screws 38.

15 The tambour 25 could not be moved in any direction over the surface of the cloth plate 19 if the pivots 37 were held stationary. On the other hand, if both arms 31 were pivotally connected to the lugs 30, instead of only one arm, as described, the tambour would be capable of a limited swinging movement even with the pivots 37 held stationary. There would, however, be no means of definitely controlling the movement of the tambour with such a construction. In order, therefore, to provide a controllable movement, either of the arms 31 is secured to the tambour with a pivotal connection and the other of the arms is rigidly secured, and the pivots 37 are both movable, as will be hereinafter more fully pointed out.

20 35 A swinging movement of the arms 34 inwardly, or toward one another, an equal amount, will cause the fabric to pass under the needle in a straight line away from the arm standard 2; while a movement of the arms 34 an equal amount in the opposite direction will cause the fabric to move in a straight line toward the arm standard 2. By correspondingly and simultaneously increasing or decreasing the movement of both arms by the same amount, the feeding of the fabric under the needle will be proportionately increased or decreased but will still be moved in a straight line in one direction or the other. However, if the amount of movement of one of the arms 34 is made greater than the amount of movement of the other arm, either in the same or in the opposite direction; or if one arm is held stationary while the other is moving, the feeding of the fabric will deviate from such a straight line in direct proportion to the difference of movement of said arms. By simultaneously increasing or decreasing the movement of both of said arms 34 by the same amount, irrespective of their relative direction and their relative extent of movement, the feeding of the fabric, and hence the length of the stitches, will be proportionately lengthened or shortened, as the case may be, but the direction of the feed will not be changed.

From the foregoing, it will be obvious that by varying the swinging movement of the pivots 37, to which the arms 34 are connected, a stitch of any desired length within predetermined limits and in any desired direction may be produced. The mechanical connections of the tambour with the pattern controlling mechanism for producing such movements will now be pointed out.

25 The pivots 37 each have on their lower ends disks 39, preferably made in one piece with their shank portions, as shown in Figures 4 and 5. These pivots are journaled at their upper portions in flat bearings 40 and at their lower ends in a plate 41 secured to the ribs 42 projecting downwardly from the bed plate. The bearings 40 preferably each have a threaded engagement with relatively large bushings 45, passing through suitable openings in the bed plate, and have 30 their portions 46 overlapping the edges of said openings to maintain the bearings and bushings in position in the bed plate. At an intermediate portion of each of the pivots 37, and secured by means of a suitable key 47, is a gear 48 meshing with a pinion 49, as shown in Figures 3 and 5. The pinions 49 are pivotally mounted on studs 50, Figures 3, 9, and 10, projecting from the widened portions 51 of the pivotal members 52 loosely mounted on the pivots 37.

35 Mounted concentrically with the pivots 37, and lying in the same horizontal plane with the gears 48, are internal ring gears 53 which also mesh with the pinions 49. The internal ring gears are secured by suitable fastening means 54 to disks 55 pivotally mounted on the pivots 37 and rotatably engaging the bushings 45. The disks 55 loosely overlie the gears 48 and pinions 49 and are loosely 40 enclosed by the annular flange portions 56 of the bushings 45.

45 The pivotal members 52 are each in slideable connection with the comparatively short sliding members 57 by means of a groove 58 in each of the pivotal members 52 and a rib 58' on each of the sliding members 57. To permit the desired reciprocating movement of the sliding members 57 with relation to the pivotal members 52, in addition to the 45 pivotal movement simultaneously with the members 52 about the pivots 37, the sliding members 57 are provided with slots 59 through which the pivots 37 freely pass. The pivotal members 52, in their pivotal movement, bear at one side on the face of flange 56 of the bushing 45, as shown in Figure 5, and at their other side are in engagement with the sliding members 57, as set forth. The sliding members 57 in turn have a sliding contact with the plate 41. In order to permit ribs 42 to be of the desired strength, the bushings 45 each have a flat portion 45' on one side thereof for engagement with the ribs and a similar flat portion 50

45' on the opposite side thereof to provide clearance for the shuttle shaft 16.

In the same transverse vertical plane with the pivots 37 are two pivots 60, similar to the 5 pivots 37 and provided with disks 61 on their lower ends. The pivots 60 preferably have a smaller shank portion than the pivots 37 and do not extend entirely through the bed plate 1. At their upper ends they are journaled in bushings 62 driven into suitable openings in the bed plate, and formed with end plates 63 to cover the pivots. At their lower ends the pivots 60 are journaled in the plate 41, as clearly shown in Figure 4. On 10 the pivots 60 are mounted pinions 64, Figure 4, having hubs 65 provided with set screws 66. The pinions 64 are of such diameter, and are so placed, as to be in mesh with the internal gear 53, but out of mesh with the 15 gears 48. The large bushings 45 are provided with suitable openings 67 to receive the hubs 65, and the disks 55 have arcuate slots 68 for receiving the pivots 60 and permitting the necessary pivotal movement of 20 the parts, as shown in Figure 3.

The pivots 37 are each provided with bushings 69 secured by transverse pins to the pivots, which pins each engage one end of a volute spring 71 and the other ends of which 30 springs pass through slots 72 in the upper part of the bushings 45. The pivots 60 are each similarly provided with bushings 73, volute springs 75 secured at their inner ends to the pins 74 and at their outer ends to 35 studs 76 projecting upwardly from the plate 41.

The sliding members 57 each have rack teeth 77 on one side thereof, Figures 3, 9, and 11, adapted to engage intermediate pinions 78 carried by pivots 79 extending 40 through the plate 41 and secured by nuts 80, as illustrated in Figure 4. An operating slide 81, Figures 4, 9, and 39, having rack teeth 82 on each side thereof, meshes with 45 the intermediate gears 78 to transmit motion to the slide members 57. To guide said power slide during its reciprocal movements, brackets 83 are provided on both sides thereof and secured by fastening means 84 to the 50 plate 41 to abut against the upward projections 85 of the power slide. These brackets preferably have cut-away portions 86 in their central portions to accommodate the intermediate gears 78. The slide 81 is connected 55 with the lower forked end of a feeding lever 87, as shown in Figures 1, 7, and 9, by two links 88 having suitable pivotal connections 89 therewith and with the slide 81. The feeding lever 87 in turn derives its motion 60 from a cylindrical cam 90 suitably keyed to the power shaft 3 in the arm standard and secured in any desired manner against movement longitudinally thereof. The cam 90 is formed with a peripheral groove 92 to 65 part to the lever 87 at each revolution of the

main shaft 3, two periods of movement and two periods of rest, with the periods of movement and rest successively alternating and each period corresponding to 90° of rotation of the cam. A development of the 70 cam 90 is illustrated in detail in Figure 32. The feeding lever 87 at its upper end is provided with a laterally extending stud 93 projecting from both sides thereof and provided on its inner end with a roller 94 working in 75 the cam groove 92.

Intermediate its ends, the lever 87 is pivotally carried on the arm standard 2 by means of a channel shaped member 95, Figures 7 and 8, secured to a filler block 96 by 80 suitable fastening means 97 to form a rectangular opening adapted to slidably receive an intermediate portion of the lever 87. The filler block 96 is pivotally secured to a slide 99 by a pivot screw 98 passing therethrough, 85 and the slide 99 is in turn carried by a grooved plate 100 fixedly secured to the inner wall of the arm standard 2 by screws 101. The slide 99 has projecting therefrom an arm 102 preferably bent upwardly to form a 90 lever and having at its end a stud portion 103 extending outwardly through the slot 104, Figure 13, in the arm standard. The stud 103 has a threaded end to receive an 95 operating clamp or knob 106. A mounting 100 of the character described for the lever 87 provides convenient means for shifting its pivotal point up or down to vary the length of the stroke of its lower forked end, for purposes which will hereinafter be more 100 fully explained. It is evident that by loosening the knob 106, the slide 99 may be shifted to any desired position in the grooved plate 100 and secured in adjusted position 105 by reclamping the knob 106.

In order to insure a construction in which the forked end of the lever 87 reaches identically the same position at the termination of each of its forward movements, which position is diagrammatically illustrated by the reference letter B in Figure 30, irrespective of the adjustment of its pivotal point, the grooved plate 100 is angularly secured to the inside of the arm standard 2 at the angle indicated by the line AB, Figure 30, and as 110 shown in Figure 1 along which line the slide 99 is adapted to be adjusted, so that the axis of pivot screw 98 is in the plane of AB, regardless of its adjusted position.

A cylindrical cam, such as the cam 90, 115 having a cam groove in its periphery, in connection with a roller and lever having a pivotal point as set forth, works incorrectly both theoretically and practically, as the lateral walls of the cam groove are formed at all points at a straight angle to the longitudinal axis of the cam, while the lever moves in the arc of a circle and presents the roller 94 at an angle gradually changing 120 relatively to the lateral walls of the cam. 125 130

groove. In order to obviate this objection, the roller 94 is made to travel in a true horizontal plane parallel to the longitudinal axis of the cam 90 or shaft 3. In order to obtain this result, there are provided two levers 107 of equal length between their pivotal points, Figures 1, 7, 40, and 41, bent as required, and pivotally secured to lugs 108 on the arm 2. The opposite ends of the levers 107 have laterally projecting studs 110 secured thereto and entering suitable apertures in a horizontally floating compensating beam 111 having a central opening to receive the outer end of the stud 93.

Referring to Figures 1, 7, 8, 40, and 41, the working of the device will be clearly understood. The cam 90, during its rotation, will cause the lever 87 to move in one direction during 90° of rotation of the cam, then rest for an equal number of degrees of rotation, then again move in the opposite direction for 90° of rotation, and thereafter again rest for a similar period. The compensating lever 111, being secured to the stud 93 at its intermediate portion, will necessarily follow the back and forth movements of the lever 87. This compensating lever 111, however, having pivotal connections with the levers 107, will cause these levers to swing in the arcs of circles, pulling with them in opposite directions the ends of the compensating lever 111, causing one end to move up while the other moves down with relation to the longitudinal axis of the cam 90, but maintaining the central portion of the compensating lever together with the upper end of lever 87 in the same horizontal plane. This is necessarily true, as the levers 107 are of the same length and the deviation of the one end of the compensating lever 111 from the longitudinal axis of the cam 90 will be compensated for by an equal deviation in the opposite direction at its opposite end. The lever 87, to adapt itself to this movement, is permitted to slide up and down in the bearing provided therefor between the members 95 and 96.

During each rotation of the shaft 3, the upper end of lever 87 is moved in a fixed distance by cam 90, irrespective of the position of its fulcrum screw 98, while the movement of the lower end and the movement of the rack slide 81 is determined by the position of the screw 98 along the longitudinal axis of lever 87 to which it is adjusted by the arm 102. It will be therefor appreciated that the throw of rack slide 81 can be varied by the up and down adjustment of fulcrum screw 98, whereby the size of the design embroidered by the machine can be varied. This enables me to produce various sized designs from the same pattern hereinafter described.

The sole purpose of the pattern mechanism hereinafter described is to control the

angular positions of slides 57 relative to the longitudinal axis of the machine or the longitudinal center of the slide 81. This angularity of slides 57 determines the extent and direction of rotation of pivots or shafts 37 ⁷⁰ through their various connections, by the reciprocation of slide 81, which shafts or pivots 37 determine the direction and extent of movement of the tambour.

Spliced to the shuttle shaft 16 at an intermediate portion thereof, is a helical driving gear 112, having hubs 113 on opposite sides thereof secured against longitudinal displacement by a set screw or the like 114. This helical gear cooperates with a similar driven gear 115, of double its size, to reduce by one-half the speed thereof, making it revolve at the same speed as the main shaft 3. The gear 115 is preferably hubbed, as illustrated in Figure 6, and mounted on a transversely extending shaft 116 journaled at its opposite ends in split bearings 117 secured to the ribs 42 of the bed plate by suitable fastening devices 118. The shaft 116 is provided with a keyway extending from one bearing 117 to the other, and by means of a suitable key 119, the helical gear 115, a set of six eccentrics or cams 120, and two collars or rings 121, are secured thereto. The shaft 116 is maintained against longitudinal movement by two collars 122, Figures 3 and 6, secured thereto by set screws or the like 123. As the helical gears are mounted on the shafts 16 and 116 at 90° one to the other, they have a tendency to move the shafts in an endwise direction. To take up this end thrust, the shaft 16 is provided with a thrust ball bearing 124 and the shaft 116 is provided with a similar bearing 125.

Extending parallel to the shaft 116, and journaled in half bearings 126, also secured to the ribs 42, is a second transverse shaft 128 on which a set of six levers 129 are pivotally mounted for movement independently thereof. The levers 129 are formed with spacing hubs and are provided with vertically extending grooves 130, Figures 5 and 6, in their longer ends to receive rollers 131 rotatably journaled therein to cooperate with the cams or eccentrics 120. The opposite or shorter ends of the levers 129 are narrowed to enter grooves 132, Figure 4, in the bell shaped brake shoes 133 loosely connected thereto by suitable pins 134. These brake shoes have on their upper faces cavities for the reception of fiber, leather, or similar disks 135 adapted to produce a braking action on the disks 39, 61 and 183 (hereinafter described). The cams 120 and the levers 129 cooperating therewith are so positioned on their respective shafts as to be in the same vertical planes with the axes of the pivots 37 and 60 and the gears 181 (hereinafter described), as shown in Figures 4 and 6.

The distance between the shaft 116 and the shaft 128 is preferably twice that which exists between the shaft 128 and the axes of the pivots 37 and 60, whereby the leverage on the brake shoes is increased. These brake shoes are operated in such manner that they are intermittently in braking engagement with the disks 39 and 61 and the disks 183 (hereinafter described) secured to 10 the gears 181; so that the pivots 37 and 60 and said gears will be held stationary under the action of said brakes at different periods determined by the cams 120. These cams 120 are continuously rotating, and when a 15 high portion or projection thereon comes in contact with the rollers 131 of the levers 129, the opposite ends of the levers cause the brake shoes to press against the disks and prevent rotation thereof. When the 20 low portions of the cams are effective on the rollers 131, the brake shoes are withdrawn by the action of light springs 136, and rotational movement of the pivots, the disks, and the parts to which they are connected, is 25 permitted. The springs 136 each have one end thereof secured in the groove 130 of the levers 129, and their opposite ends engaged by a rod 138 maintained at the edge of the plate 41 by means of suitable clamps 30 139 and screws 140, as shown in Figures 5 and 6. Between the levers 129 on the shaft 128 are mounted collars 141 to separate the levers and prevent displacement thereof. For supporting the shaft 116, a roller 143 35 is loosely mounted thereon and journaled in a bracket 144 centrally secured to the under side of the bed plate 1. The shaft 128 is likewise supported at its central portion by a split bearing 145 held on the plate 41 by 40 fastening means 146.

In order that the pressure of the brake shoes on the disks may be conveniently regulated and adjusted to enable the same to be thrown out of contact with the disks when a 45 new fabric is placed in the tambour and manual shifting thereof is required or desired, the following means is provided: The shaft 128 has its central and end portions eccentrically reduced in diameter, as illustrated in Figure 6, and has one of the eccentrically reduced portions thereof extending beyond its bearing 126 and into engagement with a crank lever 147. A suitable key 148 may be provided between the shaft 50 and the crank 147, and the crank may be held in position by a locking device 149. The crank lever has a spring pressed device comprising a sleeve 150 secured thereto for receiving a shouldered pin 151 detachably 55 carrying a knurled knob 152 at one end, and having its opposite end projecting through an opening in the crank lever. The pin 151 is normally maintained in projecting position by a suitable compression spring 153 engaging the shouldered portion thereof.

Between the crank lever 147 and the bearing 126 is provided a segmental plate 154, Figures 3, 6, and 13, having at one end an opening for the passage of the shaft 128 and at the other end an elongated opening 155 to 70 receive the protruding portion of the pin 151. The segmental plate is also preferably provided with an arcuate opening 156 for adjustment purposes, the plate being held in adjusted position by a set screw 157. It 75 will be evident that by slightly rotating the shaft 128 it will be raised or lowered due to its eccentric portions, in proportion to the eccentricity and the amount of turning movement. This enables the braking device 80 to be lowered sufficiently to make it inoperative and release the tambour for manual shifting at will. When the shaft 128 is turned back and the pin 151 again put in engagement with the opening 155 in the adjustable segment plate 154, the braking device will again be operative. 85

The adjustment just described, in combination with the releasing means, is sufficient to give satisfactory results, but it is 90 preferred to combine therewith other means for regulating the pressure of the brakes, giving them a certain amount of resiliency or elasticity, and increasing their efficiency. This is accomplished by forming the end 95 bearings 126 and the middle bearings 145, as shown in Figure 6, with slightly elongated openings fitting the shaft 128, as illustrated more particularly in Figures 33, 35, and 37. Such elongated openings permit 100 a limited vertical movement of the shaft 128 independently of the crank 147, the segmental plate 154 also being slotted to permit this movement. The collars 141 which are adjacent the bearings 126 are formed 105 with annular grooves 158. Disposed in these grooves are the ends of stiff springs 159 pivotally secured to the ribs 42 by screws 160. The opposite ends of the springs 159 engage short tension levers 162, pivotally mounted 110 on the screws 160 and provided with adjusting screws 163. By this means, the pressure of the springs 159 may be effectively regulated. The middle bearing 145 may be formed on its base with grooves 164, Figure 115 34, to clamp the free ends of a spring 165. The bottom of the bearing 145 is provided with a groove 166, to permit the opposite end of the spring 165 to bear against the shaft 128. The action of the springs 159 and 165 on the shaft 128 will cause the levers 129 to resiliently press, with the rollers 131, against the cams 120, at one end, and with the brake shoes 133 on the disks, at their opposite ends. As the braking action is 120 timed by the cams 120, as illustrated diagrammatically in Figure 29, to be effective alternately, the pressure of the springs will be evenly divided between the brakes which are in operative position only or, in other 125 130

words, those whose levers are in contact with the high portions of the cams 120. The levers 129 during inoperative periods will not be affected by the springs 159 and 165 as the rollers 131 thereof will be held in contact with the low portions of the cams 120 by the springs 136, with their brake shoes in lowered position. Due to the mounting of the levers 129, the pressure of the springs 159 and 165 with respect to the disks will be twice that exerted with respect to the cams 120. In order to render this supplemental means entirely independent of the adjustment and release effected by the crank 147 and its associated parts, the eccentrically reduced end portions of the shaft 128 are made sufficiently long to receive the collars 141, whereby the turning movement of the shaft 128 will have no effect on the 20 collars.

The spring pressed device as applied to the brakes may be varied at will, giving more or less the same result, and one modification thereof is illustrated in Figures 35 and 25 36. In this form of the invention, there are provided leaf springs 167, comprising any desired number of leaves, in place of the coiled springs 159. The springs 167 are pivotally secured to the ribs 42 by slotted 30 pivots 168 through which the springs pass, and are adjustable by means of screws 169 passing through threaded bushings in the ends of the springs and abutting the plate 41.

The foregoing mechanism comprises that 35 portion which for the sake of convenience has hereinbefore been termed the feeding mechanism. The portion of the mechanism comprising the pattern controlled feed predetermined mechanism will now be described in detail.

The sliding members 57 are provided at their rear ends with studs 170 projecting downwardly therefrom and carrying rollers 171, Figures 5 and 7. These rollers 171 are 45 in operative engagement with guide slots 172 of segments 173, Figure 6, having hubs 174, Figures 5 and 7, pivotally mounted in the plate 175 secured to the ribs 42 and lying in a plane below the plate 41. The segments 173 are maintained in such pivotal 50 position by washers 177 and screws 178 threaded into the hubs 174. The sliding members 57 in their reciprocal movement cause the rollers 171 carried thereby to travel 55 in the guide slots 172. The rear ends of the guide slots 172 are so positioned as to bring the axes of the studs 170 in line with the axes of the hubs 174 and screws 178 when the sliding members 57 reach their rearmost 60 position and at which time the lower end of lever 87 is at point B of Figure 30, or at the other end of its throw from that shown in Figure 1. This permits the segments 173 during this time to be swung without affecting the sliding members 57. The seg-

ments 173 have downwardly projecting toothed portions 179, working in the cut-away portions 180 of the plate 41, and meshing with gears 181 before briefly referred to. The gears 181 are preferably pivotally 70 mounted on screws 182 threaded in the plate 41. The heads of the screws 182 enter suitable depressions in the gears so that they do not project therebeyond, as shown in Figure 5. To the gears 181 are secured disks 183, 75 slightly larger than the gears, on which the central brake shoes 133 are intermittently pressed to brake said gears and consequently the segments 173 against any swinging movement. The opposite ends of the segments 173 are provided with elongated openings 185 in which work the upwardly projecting pin portions of the screws 186 secured to transverse slides 187. These slides 187 are in 80 sliding engagement with a groove 188 formed in the rear edge of the plate 175, at one side thereof, and in sliding engagement with a groove 189 formed in the front edge of a bar 190, at the other side thereof. The bar 190 is secured to the plate 175 by means of a 85 supporting plate 191 secured to and overlying the plate 175 and projecting therefrom to support on its lower surface the bar 190. This supporting plate 191 is preferably cut-away in such manner as not to interfere with the pivotal movement of the segments 173, as shown in Figures 3 and 6. Below each of the slides 187, and rotatably mounted on the screws 186, is a roller 193, Figures 5 and 17, which rollers are in intermittent engagement with the ends of segmental curved levers 194 each having a pivotal mounting 195 on the plate 175. The levers 194 have intergeared portions 197 so that their free ends both have a simultaneously converging or diverging movement. One end of said curved levers has a projecting portion 198, Figure 3, pivotally connected with a bifurcated block 199. This block has a pivotal connection 201 with a second bifurcated 105 block 202. Between the bifurcations of the block 202 is connected the lower end of a lever 203 having a pivotal connection 206 with a lug 205 projecting inwardly from the arm standard and forming a part thereof. 110 The lever 203 derives movement from a cam 207 rigidly secured to the main shaft 3. The upper end of the lever 203 is provided with a cam roller 208 bearing on the cam 207. A tension spring 209 holds the cam roller 115 normally in contact with the low portion of the cam 207, causing the segmental curved levers 194 to be normally in closed position, as shown in Figure 3. The function of the levers 194 is to move the segments 173 apart against the action of the tension springs 210, Figures 3 and 6, by bearing at their ends 120 against the rollers 193, and then, during their converging or closing movement, to permit the segments 173 to gradually close under the 125

influence of the springs 210. This closing movement of the segments 173 continues until stopped by the pattern, as will be hereinafter more fully pointed out.

5 A pattern control is provided to cause the segments 173 to be variably positioned in accordance with the pattern under the action of the springs 210 when released by levers 194 during their converging or inward movement. This variable positioning of the segments occurs just prior to each feeding movement of the tambour and pre-determines the direction and extent of each succeeding feeding movement thereof. This 10 pattern control, in its illustrated form, comprises two brackets 212 secured to the plate 175 and the bar 190 and projecting downwardly therefrom, as shown more particularly in Figures 5, 17, 18, and 19. The lower 15 parts of the brackets 212 are provided with openings in which are secured bearings or bushings 213 rotatably receiving a pattern shaft 214. This pattern shaft receives continuous rotary movement from the shuttle 20 shaft 16 by means of a worm 215 keyed thereto and in engagement with a worm wheel 216. The worm wheel 216 is rotatably connected, in any desired manner, to a spur gear 217, and both the worm gear and the 25 spur gear are carried by a stub shaft 218 secured in the bed plate of the machine and projecting downwardly therefrom. The spur gear 217 in turn meshes with a pinion 219 mounted on a vertical shaft 220 journaled at its upper end in the bed plate 1 and at its lower end in a bearing 221 carried by a bracket 222.

40 The lower end of the shaft 220 has secured thereto a worm 223 adapted to drive a worm gear 224 rotatably mounted on an extension on one of the bearings 213, as shown in Figure 17. The worm gear 224 is held against endwise movement by a hub 225 contacting with one of the brackets 212, and by a bracket 226 extending over the gear 45 from one of the brackets 212. The gear 224 is held in operative connection with the pattern shaft 214 by means of a transverse pin 228 passing through the pattern shaft 50 and engaging a groove in the outside hub 229 of the gear 224. Owing to the double worm drive, it will be apparent that the speed of rotation of the pattern shaft 214 as compared to that of the main shaft 3, is 55 very low. On the pattern shaft between the bearings 213, is mounted a pattern carrying wheel comprising a relatively thin central body 231 having spacing hubs 232 bearing against the inwardly projecting sides of the bearings 213, and carrying pins 233 equally 60 spaced on its periphery for engagement with the pattern tape 234. An annularly grooved roller 235, Figures 6 and 17, rotatably mounted in the bracket 236 carried by a leaf spring 237 secured in any desired 65 man-

ner to the plate 175, is provided to firmly hold the pattern tape against the periphery of the pattern wheel.

The pattern tape is provided with openings 240, as shown in Figure 31, centrally located and equi-distantly spaced, to receive the pins 233 of the pattern wheel. The tape is provided on both edges thereof with a series of grooves 241 cut at right angles to the tape and closely but equally spaced on 70 both sides thereof. These cuts or grooves are of variable depth, forming configurations or patterns of such nature that when the tape is fed through the machine they will cause the tambour or cloth carrying device 75 to be moved in the required direction and to the required extent to produce a given design. These pattern edges are intermittently operative on the slides 187 through the medium of tongues 242, Figures 14, 17 80 and 18, pivotally mounted on studs 243 projecting downwardly from the slides 187. The tongues 242 work in grooves 244 formed in the base of each of the brackets 212, and are held in engagement with the studs by 85 the bottoms of said grooves. The thin portions of the tongues are adapted to engage the pattern, and may be reinforced in any desired manner to give increased strength, as shown in Figures 15 and 16 illustrating 90 different forms of reinforced tongues 242^a and 242^b. The tongues are also provided with openings 245 receiving pins 246, projecting downwardly from the slides 187. The pins 246 are preferably of less diameter 95 than the diameter of the holes 245 in which they work, whereby a slight swinging movement of the tongues, limited only by said pins, is permitted. Light coiled springs 247 surrounding the pins 246 and having one 100 end secured to the slides 187 and the opposite end projecting downwardly to abut against one side of the tongues, are provided for normally holding the tongues in such position that one side of each of the 105 openings 245 will engage the stop pins 246, in which position the tongues extend at right angles to the pattern. The springs 247 are effective for urging the tongues in a direction opposite to the direction of rotation of 110 the pattern wheel.

115 Equidistant from each of the edges of the pattern and the maximum depth of the grooves 241, is an imaginary or actual line termed a "zero line." If the pattern, or any portion of it, is cut away on both sides exactly to the zero line and the pattern fed through the machine in the usual manner, the pattern will be effective for producing 120 no movement of the feeding mechanism and consequently of the cloth-carrying tambour. During the inward movement of the curved levers 194, the segments 173 will follow, as before described, under the influence 125 of the springs 210, until the tongues 242 130

- come into contact with the pattern. Engagement between the edges of the pattern and the tongues 242 positively stops further inward movement of the segments 173, but permits the levers 194 and 203 to continue their converging movement under the influence of the tension spring 209. Due to the provision of the spring pressed pivotal mounting 246 for the tongues 242, no harm will result either to the pattern or to the tongues, although the pattern has a continuous movement and the tongues an intermittent movement. The thin ends of the tongues will enter the grooves in the pattern and while in such position the travel of the pattern will cause the tongues to swing in opposition to the springs 247, but as soon as the tongues are withdrawn they will be reset by the action of said springs.
- 20 For each operation of the tongues, the pattern will rotatably advance a distance only slightly greater than the thickness of the thin portions of the tongues in order to provide clearance therefor.
- 25 Owing to this construction of the pattern controlled mechanism, quite a number of stitches may be produced from every inch of pattern, and a continuous movement of the pattern may be effectively utilized.
- 30 Such a movement of the pattern is incomparably better than an intermittent movement such as produced by a pawl and ratchet, or some such similar means, as it is noiseless and prevents double movement, slipping and back movement, thereby increasing both the efficiency and accuracy of the machine. A further important advantage of the present pattern control arises from the fact that the pattern not only does not move the feeding mechanism directly, as in many pattern controlled machines, a separate and distinct connection from the power shaft effecting this movement; but it does not even move the feed predetermining mechanism, as is the case, for example, in my prior Patent No. 1,354,919. This movement of the feed predetermining mechanism is also accomplished directly by the power shaft, as will be hereinafter more fully pointed out. The pattern with its configurations acts merely in the capacity of a stop to the closing movement of the segments 173, causing them to assume different angular or oblique positions by means of which movement of the cloth-carrying tambour is controlled. This construction permits the use of relatively light and inexpensive pattern material and insures a maximum number of stitches per inch of pattern.
- 60 To prevent the fabric from being lifted from the bed plate of the machine with the needle when the stitches are being tightened, there is provided a presser foot 249 having a circular rubber lined base 250 placed concentrically with relation to the needle, as

clearly shown in Figure 20. The presser foot is mounted at its lower portion in a bushing 251 and at its upper portion in an adjustable threaded bushing 252. Surrounding the presser foot and abutting a collar 254 secured thereto, is a compression spring 253, the compression of which may be regulated by adjusting the position of the bushing 252 to vary the effective pressure of the base 250 on the cloth. During the operation of the machine, the presser foot is raised and lowered by a crank lever 255 carrying a roller 256 on one end in operative engagement with the periphery of a cam 257 on the shaft 8. This cam 257 is shaped and timed to raise the presser foot just before commencement of the feeding movement of the tambour and to lower the same as soon as the feeding movement is completed. The opposite end of the crank 255 is in engagement with a roller pin 258 projecting laterally from the collar 254. The presser foot may be provided with the usual lifter 259 for raising the same above the bed plate and maintaining it in raised position to permit manual adjustment of the cloth as required.

The operation of the machine is as follows:

When the cam 90 is rotated, the feeding lever 87 and the central slide 81 connected thereto by the links 88 are caused to reciprocate. This movement is transmitted to the sliding members 57 through the intermediate gears 78, but in a direction opposite to the direction of reciprocation of the slide 81. As the sliding members 57 reciprocate, the rollers 171 carried on the under sides thereof by the studs 170, will also reciprocate in the guide slots 172 in the segments 173. When the tongues 242 are in contact with the pattern on the zero line, the guide slots 172 of the segments 173 will be positioned parallel to the shuttle shaft 16. However, when the tongues 242 are in contact with the configurations of the pattern at any point other than the zero line, either to one side thereof or the other, the guide slots 172 will extend obliquely or angularly in one direction or the other. As the position of the segments 173 is directly determined by the point of contact of the tongues 242 with the pattern, the direction and amount of the swinging movement of the segments 173 will in every instance be dependent upon the direction and amount of deviation of the tongues 242 from the zero line of the pattern.

When the rollers 171 are at the rear end of the guide slots 172, where they are in concentric relation with respect to the hubs 174, as shown in Figures 5 and 6, which hubs constitute the pivotal mountings for the segments 173, these segments will be free to swing in either direction without producing any movement of the sliding members 57.

The cam 90 which effects the reciprocating movement of the sliding members 57, and the cam 207 which permits the segments 173 to come into successive engagement with the pattern, are therefore so positioned on the main shaft 3 that each setting of the tongues 242 against the pattern edges will be made during the period in which the rollers are in this concentric relationship.

- 10 The sliding members 57 also always extend parallel to the shuttle shaft 16 when the rollers 171 are at the rear end of the slots 172, irrespective of the swinging movement or position of the segments 173. When the 15 sliding members during their reciprocal movement cause the rollers 171 to travel to the opposite ends of the slots 172, if the slots are parallel to the shuttle shaft, the sliding members will be maintained parallel to 20 the shuttle shaft. On the other hand, if the guide slots extend obliquely to the shuttle shaft by reason of the engagement of the tongues 242 with the pattern at points not in the zero line, the rollers 171 during their 25 forward movement are forced to travel in the oblique line of the guide slots. This produces a gradual swinging of the sliding members 57 about the pivots 37 during their reciprocal movement and in addition to such 30 reciprocal movement. This swinging movement of the slides 57 continues until the rollers 171 reach their most advanced positions in the guide slots. The parallel position of the members 57 will thereafter be restored 35 as soon as the rollers 171 are again brought to the rear ends of the guide slots. This swinging movement of the sliding members 57 is in turn transmitted to the pivotal members 52 through the grooves and projections 40 58 and 58'. In this manner, the swinging or pivotal movement of the pivotal members 52 is produced by the power shaft 3 through the connections described, and the direction and extent of movement is governed by the 45 pattern. The feed predetermining mechanism is inoperative engagement with the feeding mechanism when the rollers 171 are in concentric position with relation to the hubs 174, and is in operative engagement 50 therewith when the rollers are at any other position within the guide slots.

The pivotal members 52 in their swinging movement cause the pinions 49 carried thereby to rotate either in one direction or the 55 other by reason of their engagement with the spur gears 48 on one side and their engagement with the internal ring gears 53 on the opposite side. The direction and extent of the rotary movement of the pinions 60 49 is dependent upon the direction and extent of movement imparted to the pivotal members 52, as will be apparent.

The braking device, acting on the disks 39, 61, and 183, causes these disks and their associated mechanism to be braked during cer-

tain periods, as illustrated diagrammatically in Figure 29. When the brakes press on the disks 39, the pivots 37 and the gears 48 are held stationary. When the brakes act on the disks 61, the pivots 60, pinions 64, and 70 internal gears 53 are held stationary. When the brakes are effective on the disks 183, the gears 181 and segments 173 meshing therewith are held stationary. As the brakes are removed from these disks, full 75 pivotal and swinging movement is restored to the respective mechanisms.

The braking of the segments 173, through the disks 183, does not occur until after the curved levers 194 have completed their converging movement, thus permitting the segments to swing inwardly until stopped by the engagement of the tongues with the pattern. This braking is, however, effective 80 immediately after the conclusion of the converging movement and just prior to the time the sliding members 57 commence their forward stroke. This secures the segments against any accidental movement during 85 such forward movement of the slides 57, 90 which forward movement, as has been explained, produces the feeding movement of the cloth-carrying tambour. The release of the disks 183, and consequently of the segments 173, begins immediately after the completion 95 of the forward movement of the sliding members.

When the spur gears 48 are in braked position, through the disks 39, the internal 100 gears 53 are free to revolve, and when released, the internal gears are braked and the spur gears 48 free to revolve. The change from braking to unbraking, or releasing position, is not performed simultaneously, as 105 the cams 120 are timed to start the unbraking action 45° later than the braking action. This overlap gives the rollers 131 of the 110 brakes time to roll up the inclined portions of the cams 120 and holds the disks 39 and 61 against any undesirable movement during the change of the brakes from operative to inoperative position. These braking and unbraking operations are, however, performed only at such times as the sliding and 115 pivotal members 57 and 52, respectively, are held stationary due to the 90° rest periods provided by the cam 90.

When the pivotal members 52 are in position parallel to the shuttle shaft, which position they occupy every time the rollers 171 120 reach the rear ends of the guide slots 172, they are in the position designated as the zero position. During the forward movement of the sliding members and, therefore, 125 the swinging movement of the pivotal members from such zero position, the timing of the braking devices is such as to brake the internal gears 53 and permit the spur gears 48 to rotate; while during the backward movement of the sliding members and, 130

therefore, the swinging movement of the pivotal members toward or actually to the zero position, the internal gears 53 are free to rotate and the spur gears 48 are held stationary.

From the foregoing it will be apparent that during the swinging movement of the pivotal members 52 in either direction from the zero position, the pinions 49 carried thereby will be in meshing engagement with the stationary internal gears 53 on one side and loose gears 48 on the opposite side. This will cause the pinions 49 to rotate the loose gears 48 in proportion to the swinging movement of the pivotal members 52, and thereby rotate the pivots 37 to which the cloth-carrying tambour is connected. During the swinging movement of the pivotal members 52 back to zero position, the stationary gears 48 will cause the pinions 49 to continue rotation in the same direction and thus rotate the internal gears 53 in a direction opposite to that in which the spur gears 48 were rotated.

25 The pivots 37 are effective for imparting movements to the tambour in any direction and to any extent in a given horizontal plane, from minimum to maximum, when the internal gears are braked, while the internal gears when released assist in the resetting of the parts for the succeeding stitch.

By means of the knob 106, the pivotal mounting of the feeding lever 87 may be adjusted to different positions causing the reciprocation of the slide 81, and thereby the reciprocation of the sliding members 57, may be increased or decreased. As the forked end of the lever 87 always reaches exactly the same point at the end of its forward movement, irrespective of the adjustment of its pivotal mounting, the rollers 171 will also always reach the position of concentric relationship with the hubs 174 at the ends of their backward movement. 40 When the rollers 171 during their forward movement reach the front ends of the guide slots 172, the oblique positions of the segments will cause the maximum pivotal movement of the members 52, but when the rollers 171, in their forward stroke, do not reach the front ends of the guide slots 172, due to the adjustment of the pivotal mounting of the feeding lever, the pivotal movement of these members 52 will be proportionately reduced, although the oblique position of the segments is the same. As the adjustment of the knob 106 does not change the relative position of the segments 173, the position of which is controlled only 45 by the pattern, and the adjustment of the rearward stroke produces exactly the same change in the length of stroke of the two sliding members 57, the direction of movement of the tambour will not be altered, but the amount of movement thereof will

be proportionately increased or decreased. Thus a design reproduced from a given pattern may be made smaller or larger at will, as desired.

70 If all of the gears employed in the present construction were arranged to be rotated continuously in one direction, there would be constant pressure on one side of the teeth only, and any play which might exist between the teeth would not do any harm. 75 As the direction of rotation of the gears is, however, frequently reversed, such play between the teeth is both perceptible and objectionable. It is very difficult in actual practice to cut and assemble gears with perfect accuracy so as to avoid such play between the teeth when the direction of rotation of the gears is changed. Even if practicable, such play is bound to appear after the gears have been in use for some time and gradually increases, thereby gradually increasing the error in the movement transmitted by the gear train. As a small amount of play or loose motion between the teeth of the gear trains in the present machine is amplified by reason of the relative length of the arms 34 and the diameter of the gears 48, and also by the number of gears employed, the total play, unless compensated, would be very objectionable. It 80

is to overcome this play that there are provided springs 71 for the pivots 37 and the springs 75 for the pivots 60. These springs 71 and 75 are wound in such directions as to work one against the other. They are preferably of substantially the same strength whereby a balanced condition is produced. Due to this balance, the tambour may be easily adjusted manually by turning the knob 152 to render the braking device ineffective, as the springs produce no movement of the tambour although they do exert a pressure on one side of the teeth of the meshing gears 64, 53, 49, and 48. In the present construction, the pressure of the 100 springs is evenly divided between three points, namely, gears 64 and 53, gears 53 and 49, and gears 49 and 48. When, however, the knob 152 is returned to its original position, thereby restoring the effectiveness of the braking device, this balanced condition will no longer exist as the brakes will press either on the disks 39 or 61 to which the springs 71 and 75 are respectively connected, thereby restoring the individual effect of one spring or the other. When the disks 61 are braked, causing the springs 75 to be inoperative, the springs 71 will cause one side of the teeth of the gears 48, 49, 53, and 64 to be in pressed contact, while when the disks 39 are braked, rendering the springs 71 ineffective, the springs 75 will cause the same side of the teeth of the gears to be in pressed contact, although the spring action at such times is effective, from the 105 110 115 120 125 130

opposite side of the gear train. The winding of these springs is obviously such as to cause one of the springs to wind as the other unwinds. By reason of this construction, the motion of each of the gear trains is accurately and exactly transmitted to the cloth-carrying tambour.

When it is desired to produce a plurality of designs composed of a comparatively small number of stitches, such as a flower, a monogram, or the like, there may be substituted for the pattern tape a pattern wheel 260, such as shown in Figure 23, having a removable rim 261 grooved in a manner similar to the pattern tape and suitably secured to the wheel. Such a rim may be easily replaced by other rims to produce different designs. As the pattern advances only a little more than the width of the thin ends of the tongues 242, during each operation of the tongues, a considerable number of stitches may be produced from a single pattern rim.

In order that the pattern rim may be composed of a plurality of links in the form of units, to control a single stitch or number of stitches in succession, a form of pattern wheel such as illustrated in Figures 21 and 22 may be provided. According to this form of the invention, there is provided a pattern unit 262, Figure 24, to control a single stitch, or a link 263 to control two or more stitches of the same length and direction. These units or links each comprise a central body 264 having a small depending projection 265, different kinds of which are illustrated in Figures 25 and 26, and two laterally extending portions 266. These laterally extending portions 266 form the stops for the tongues, and therefore are of different lengths to produce, when assembled, the desired configurations. The units may obviously bear identifying indicia permitting their selection and assembly. These units of typelike form are assembled in a wheel 267 comprising a disk 268 having a hubbed portion 269, and a second disk 270 mounted on the hub. These disks form between them a centrally located, peripherally extending groove for the pattern units. The disk 268 may be provided with an undercut groove 271, and the disk 270 with a radially extending opening 272; and the disks may be secured in cooperative relation by suitable clamping screws 273. To assemble the units in the pattern wheel, the clamping screws 273 are removed, a unit is placed in the peripheral groove through the opening 272 so that its depending portion 265 enters the undercut groove 271; a slight turn is then given to the disk 270 and the operation repeated until the peripheral groove is filled. The clamping screws 273 are then replaced and the units clamped in position. Any desired form of slide 274 may be provided for closing the slot 272.

For putting "in figures" or making designs preparatory to the production of a pattern, the cloth-carrying tambour and its operating arms may be removed from the pivots 37 by loosening the set screws 38 and placing the entire mechanism on pivots 285 journaled in a plate 286. These pivots extend through the plate and carry arms 287, which arms are movable between the plate 286 and a lower plate 288 clamped in spaced relationship about an intermediate spacing member 289. At their outer ends the arms 287 are curved upwardly and over the edge of the plate 286, and provided with an index line 290 corresponding with scales 291 formed on the plate 286 adjacent its periphery. These scales may be graduated in thousandths of an inch and run from zero to any desired number of thousandths on both sides of the zero line. The cloth-carrying tambour may be removed from the tambour arc and a pointer 292 secured thereto in such manner that its point occupies a position corresponding to the center of the tambour. The design to be reproduced is then clamped on the plate 286 and the pointer 292 manually moved over its surface. The amount and direction of such movement from the zero lines is read by the operator and tables compiled therefrom. From these tables the desired patterns may be easily produced.

As shown in the drawings, the machine may be enclosed to protect the operator and fabric being embroidered, by providing plates 295 at the sides and ends thereof, and a plate 296 at the bottom.

The advantages of the present invention arise from the provision of a sewing embroidery machine having a continuously operated pattern and provided with both feed predetermining and feeding mechanisms, the movements of which are accurately and positively determined and transmitted to the material being embroidered.

I claim:

1. An embroidering machine, comprising a needle, a bed plate, a power shaft, means for holding the fabric to be embroidered in stretched condition, a fabric feeding mechanism for moving the stretched fabric variable amounts in any desired direction radially of the needle, a feed predetermining mechanism, a pattern cooperating with said feed predetermining mechanism for limiting the movement thereof in one direction, means for positively moving the feeding mechanism, and means separate from the pattern for setting the feed predetermining mechanism by the power shaft in accordance with the pattern, substantially as described.

2. An embroidering machine, comprising a needle, a bed plate, a power shaft, a fabric feeding mechanism for moving the fabric variable amounts in any desired direction radially of the needle, a feed predetermining

- mechanism intermittently in operative and inoperative engagement with said feeding mechanism, a pattern cooperating with said feed predetermining mechanism, means for 5 moving the pattern, means for positively moving the feeding mechanism and means for setting the feed predetermining mechanism by the power shaft in accordance with the pattern, substantially as described.
- 10 3. An embroidering machine, comprising a bed plate, a power shaft, a feeding mechanism for moving the fabric to be embroidered variable amounts over said bed plate, a feed predetermining mechanism cooperating 15 therewith, means for positively moving said feed predetermining mechanism the same distance in one direction by the power shaft between each feeding movement, means for variably limiting the movement of said feed 20 predetermining mechanism in the opposite direction to vary the feeding movement, and means for positively moving said feeding mechanism by the power shaft after each 25 operation of the feed predetermining mechanism, substantially as described.
4. An embroidering machine, comprising a bed plate, a power shaft, a feeding mechanism for moving the fabric to be embroidered variable amounts in any direction over 30 the bed plate, means for positively moving said feeding mechanism by the power shaft, a feed predetermining mechanism for controlling the direction of feeding movement of the feeding mechanism, a pattern for determining 35 the amount of movement of the feed predetermining mechanism in one direction, and means for moving said feed predetermining mechanism in the opposite direction by the power shaft clear of the pattern, substantially as described.
- 40 5. An embroidering machine having a power shaft, a fabric feeding mechanism, a feed predetermining mechanism for said feed mechanism, a pattern for determining 45 the position of the predetermining mechanism, and means for moving the predetermining mechanism toward and from the pattern, substantially as described.
- 50 6. An embroidering machine, comprising a bed plate, a power shaft, a fabric feeding mechanism, a feed predetermining mechanism intermittently in operative and inoperative engagement with said feeding mechanism, a pattern, means for moving said feed 55 predetermining mechanism toward and from the pattern when the same is in inoperative engagement with the feeding mechanism to set said predetermining mechanism, and means for operating said feeding mechanism when the feed predetermining mechanism is in operative engagement therewith to feed the fabric in accordance with the setting of said feed predetermining mechanism, substantially as described.
- 60 7. An embroidering machine, comprising

a bed plate, a power shaft, a fabric feeding mechanism, a feed predetermining mechanism intermittently in operative and inoperative engagement with said feeding mechanism, a pattern, means for moving said feed predetermining mechanism toward and from the pattern when the same is in inoperative engagement with the feeding mechanism to set said predetermining mechanism, and means for operating said feeding mechanism by said power shaft when the feed predetermining mechanism is in operative engagement therewith to feed the fabric in accordance with the setting of said feed predetermining mechanism, substantially as described. 70

8. An embroidering machine, a power shaft, a fabric feeding mechanism, a feed predetermining mechanism intermittently in operative and inoperative engagement with said feeding mechanism, a pattern for limiting the movement of said feed predetermining mechanism in one direction during such inoperative engagement, means for moving said feed predetermining mechanism clear 80 of the pattern in the opposite direction by said power shaft when the same is in inoperative engagement with the feeding mechanism, and means for operating said feeding mechanism by said power shaft when the feed predetermining mechanism is in operative engagement therewith to feed the fabric in accordance with the setting of said feed predetermining mechanism, substantially as described. 90

9. An embroidering machine, comprising a bed plate, a power shaft, a fabric feeding mechanism, a feed predetermining mechanism, a pattern cooperating with said feed predetermining mechanism, means for operating both of said mechanisms by the power shaft, and braking means effective at alternate intervals on said mechanisms, substantially as described. 100

10. A material holding means for embroidering machines, comprising a tambour arc, a tambour carried thereby, an arm rigidly connected at one end to said arc, a second arm pivotally connected at one end to said arc, and independent means for moving each 105 of said arms, substantially as described.

11. A material holding means for embroidering machines, comprising a tambour arc, a tambour detachably secured thereto, an arm rigidly connected at one end to said arc, a second arm pivotally connected at one end to said arc, and independent means for moving each of said arms, substantially as described. 120

12. A material holding means for embroidering machines, comprising a tambour arc, a tambour, means detachably connecting said tambour and tambour arc, radially disposed positioning pins cooperating with said means, an arm rigidly connected at one end 125 130

to said arc, a second arm pivotally connected at one end to said arc, and means for moving said arms, substantially as described.

13. An embroidering machine, comprising a bed plate, pivots cooperating therewith, an arm rigidly secured to each of said pivots, arms pivotally secured to each of said first mentioned arms, a material holding device rigidly secured to one of said second mentioned arms and pivotally connected to the other, a power shaft, and means for moving said pivots by said power shaft, substantially as described.

14. An embroidering machine, comprising a bed plate, pivots cooperating therewith, an arm rigidly secured to each of said pivots, arms pivotally secured to each of said first mentioned arms, a material holding device rigidly secured to one of said second mentioned arms and pivotally connected to the other, a power shaft, means for moving said pivots by said shaft, and pattern controlled means cooperating with said first mentioned means for varying the movement of said pivots, substantially as described.

15. An embroidering machine, comprising a bed plate, pivots cooperating therewith, an arm rigidly secured to each of said pivots, an arm pivotally secured to each of said first mentioned arms, a material holding device rigidly secured to one of said second mentioned arms and pivotally connected to the other, each pair of arms being adapted to swing variable amounts in either one direction or the other independently of the other pair of arms under the influence of said pivots, a power shaft, and means for moving said pivots by said power shaft, substantially as described.

16. An embroidering machine, comprising a bed plate, pivots cooperating therewith, an arm rigidly secured to each of said pivots, an arm pivotally secured to each of said first mentioned arms, a material holding device rigidly secured to one of said second mentioned arms and pivotally connected to the other, each pair of arms being adapted to swing variable amounts in either one direction or the other independently of the other pair of arms under the influence of said pivots, a power shaft, means for moving said pivots by said power shaft, and pattern controlled means for producing a variable movement of said first mentioned means, substantially as described.

17. In an embroidering machine, the combination with the bed plate and power shaft thereof, of a feeding mechanism, said feeding mechanism comprising a pair of pivots, a spur gear rigidly carried by each of said pivots, an internal gear loosely carried by each of said pivots, a pivotal member cooperating with each of said pivots, a pinion carried by each of said pivotal members in contact with said spur gears and internal

gears, sliding members cooperating with said pivotal members, means for preventing movement of the internal gears during movement of the sliding members in one direction, means for preventing movement of the spur gears during movement of the sliding members in the opposite direction, and means for moving said sliding members, substantially as described.

18. The combination with an embroidering machine having a bed plate and power shaft, of a feeding mechanism for feeding the fabric to be embroidered in any direction over said bed plate, said feeding mechanism comprising a plurality of relatively movable parts, means for breaking the movement of certain of said parts during the feeding operation, and means for braking the movement of other parts of said mechanism during the resetting of said mechanism, substantially as described.

19. An embroidering machine, comprising a bed plate, a power shaft, a feeding mechanism, a feed predetermined mechanism for producing a variable movement of the feeding mechanism, a pattern for determining the setting of the feed predetermined mechanism, two sets of braking means alternately operable for braking the feed predetermined mechanism in its set position, and means for operating the feeding mechanism while the feed predetermined mechanism is so braked, substantially as described.

20. An embroidering machine, comprising a bed plate, a power shaft, a feeding mechanism for feeding the fabric to be embroidered in variable amounts in any direction over the bed plate, said feeding mechanism comprising gear trains, and means for preventing play between the gears of said trains, substantially as described.

21. An embroidering machine, comprising a bed plate, a power shaft, a main slide carried by said bed plate, a pivoted lever for transmitting movement from said shaft to said slide, means for adjusting the position of said pivot to vary the length of the stroke of said slide, a fabric feeding mechanism positively operated by said slide, and a feed predetermined mechanism cooperating with said feeding mechanism for controlling the direction of movement of the fabric to be embroidered, substantially as described.

22. An embroidering machine, comprising a bed plate, a power shaft, a fabric feeding mechanism for moving the fabric variable amounts over the bed plate in any direction parallel thereto, a feed predetermined mechanism, a pattern co-operating with said feed predetermined mechanism, means for continuously operating said pattern, and means for intermittently operating both of said mechanisms by the power shaft to set the feed predetermined mechanism relative to the pattern, and to actuate

the feed mechanism in accordance with such setting, substantially as described:

23. An embroidering machine, comprising a bed plate, a power shaft, a fabric feeding mechanism for moving the fabric in any desired direction parallel to said bed plate, a pattern, a feed predetermining mechanism having tongues adapted to engage said pattern to control the setting of said feed predetermining mechanism, mechanism for setting the predetermining mechanism relative to the pattern, and means for operating all of said mechanisms by the power shaft, substantially as described.
24. An embroidering machine, comprising a bed plate, a power shaft, a fabric feeding mechanism, a feed predetermining mechanism, means for operating both of said mechanisms by the power shaft, a pattern effective as a stop for limiting the movement of said feed predetermining mechanism in one direction to control the direction of feeding movement of the feeding mechanism, and means for moving the feed predetermining mechanism relative to the pattern, substantially as described.

25. An embroidering machine, comprising a bed plate, a power shaft, a feeding mechanism, a feed predetermining mechanism, means for operating both of said mechanisms by the power shaft, and means operating in timed relation to said mechanisms for intermittently braking the movement of both of said mechanisms, substantially as described.

26. An embroidering machine, comprising a bed plate, a power shaft, a feeding mechanism, a feed predetermining mechanism, means for operating both of said mechanisms by the power shaft, means operating in timed relation to said mechanisms for intermittently braking the movement of the same, and means for rendering said braking means inoperative to permit manual operation of the feeding mechanism, substantially as described.

27. An embroidering machine, comprising a bed plate, a power shaft, a pattern having grooves in the opposite edges thereof, a feed predetermining mechanism, pivotal members carried by said mechanism for engagement with the grooves in said pattern to determine the setting of said mechanism, means for continuously moving said pattern by said power shaft, means for intermittently moving said feed predetermining mechanism by said power shaft relative to the pattern, a feeding mechanism cooperating with said feed predetermining mechanism and having its feeding movement controlled thereby, and means for moving said feeding mechanism by said power shaft, substantially as described.

28. An embroidering machine, comprising a bed plate, a power shaft, a fabric feeding

mechanism adapted to move the fabric over the bed plate as desired, a feed predetermining mechanism controlling the feeding movement of said feeding mechanism, said feed predetermining mechanism having a zero operating position and a plurality of positive operating positions, a pattern having a zero portion controlling the setting of the feed predetermining mechanism in zero operating position and portions displaced relatively thereto for setting the feed predetermining mechanism in positive operating position, means for operating the feeding mechanism by the power shaft, means for moving the feed predetermining mechanism in one direction by the power shaft relative to the pattern, and means carried by said feed predetermining mechanism for engaging the pattern during the movement in the opposite direction, whereby said pattern is effective as a stop for determining the position assumed by said feed predetermining mechanism, substantially as described.

29. An embroidering machine, comprising a bed plate, a power shaft, a fabric feeding mechanism for moving the fabric in any desired direction over said bed plate, a continuously moving pattern, a feed predetermining mechanism for controlling the setting of said feed predetermining mechanism, swinging tongues on the predetermining mechanism adapted to engage said pattern and to move therewith and having spring means for resetting said tongues during the setting of the predetermining mechanism as controlled by the pattern, and means for operating both of said mechanisms by the power shaft, substantially as described.

30. An embroidering machine, comprising a bed plate, a power shaft, a fabric feeding mechanism for moving the fabric in any desired direction over said bed plate, a pattern means for continuously moving the pattern, a feed predetermining mechanism having tongues adapted to engage said pattern at substantially right angles to its edges for controlling the setting of said feed predetermining mechanism and to move with the pattern, and means for operating both of said mechanisms, to set the predetermining mechanism in accordance with the pattern and to move the feeding mechanism in accordance with such setting, substantially as described.

31. An embroidering machine, comprising a bed plate, a power shaft, a fabric feeding mechanism for moving the fabric in any desired direction over said bed plate, a pattern, means for continuously moving the pattern, a feed predetermining mechanism having spring pressed tongues adapted to engage said pattern at substantially right angles to its edges for controlling the setting of said feed predetermining mechanism and to move

- with the pattern, and means for operating both of said mechanisms by the power shaft, to set the predetermining mechanism in accordance with the pattern and to move the feeding mechanism in accordance with such setting, substantially as described.
32. An embroidering machine, comprising a bed plate, a power shaft, a fabric feeding mechanism for moving the fabric in any desired direction over said bed plate, a pattern, means for continuously moving the pattern, a feed predetermining mechanism having pivotally mounted spring pressed tongues adapted to engage said pattern at substantially right angles to its edges for controlling the setting of said feed predetermining mechanism and to move with the pattern, and means for operating both of said mechanisms by the power shaft, to set the predetermining mechanism in accordance with the pattern and to move the feeding mechanism in accordance with such setting, substantially as described.
33. An embroidering machine, comprising a bed plate, a power shaft, a fabric feeding mechanism for moving the fabric in any desired direction, a pattern, means for continuously moving said pattern, a feed predetermining mechanism having pivotally mounted spring pressed tongues adapted to engage said pattern to control the setting of the feed predetermining mechanism and arranged to permit the continuous movement of the pattern, and means for intermittently operating both of said mechanisms by the power shaft independent of the pattern, substantially as described.
34. An embroidering machine, comprising a bed plate, a power shaft, a fabric feeding mechanism for moving the fabric in any desired direction, a pattern, means for continuously moving said pattern, a feed predetermining mechanism having pivotally mounted spring pressed tongues adapted to engage said pattern to control the setting of the feed predetermining mechanism and arranged to permit the continuous movement of the pattern, and means for intermittently and alternately operating both of said mechanisms, independent of the pattern, substantially as described.
35. An embroidering machine, comprising a bed plate, a power shaft, a feeding mechanism, a feed predetermining mechanism, means for intermittently operating both of said mechanisms, resilient means for intermittently braking each of said mechanisms, and means for adjusting the position of said braking means, substantially as described.
36. An embroidering machine, comprising a bed plate, a power shaft, a feeding mechanism, a feed predetermining mechanism co-operating therewith, a pattern, means for moving the pattern, means for setting the feed predetermining mechanism with rela-

tion to the pattern to control the movement of the feeding mechanism, means for operating the feeding mechanism after each setting of the feed predetermining mechanism to produce a stitch of the desired length and in the desired direction, and means permitting the re-setting of the feeding mechanism between successive stitches, substantially as described.

37. An embroidering machine, comprising a bed plate, a power shaft, fabric feeding mechanism, means for operating said mechanism, a feed predetermining mechanism for determining the movement of said feeding mechanism, a pivoted lever for operating said feeding mechanism, a cam on said power shaft and cooperating with said pivoted lever, and a correction device cooperating with said lever for causing the upper end thereof to move in a line parallel to the longitudinal axis of said cam under the action of said cam, substantially as described.

38. A feed control mechanism for an embroidering machine comprising a double faced pattern each face having control portions in different planes, the control portions on each face being on opposite sides of a zero plane, the two zero planes being parallel to each other, a feed predetermining mechanism having two guides for a fabric feed and arranged to be moved independently of each other, to different and opposite angles on opposite sides of two parallel planes, two contact devices on said predetermining mechanism for engaging the control portions on the pattern, for setting the guides in parallelism when the contact devices both engage control portions on the zero planes of the pattern and to vary the angles of said guides in accordance with the variations of the control portions on opposite sides of the zero planes, and means independent of the pattern for actuating said contact devices in both directions, substantially as described.

39. A feed control mechanism for an embroidering machine, comprising a double faced pattern each face having control portions in different planes, the control portions of each plane being on opposite sides of a zero plane, the two zero planes being parallel to each other, a feed predetermining mechanism having two guides for a fabric feed and arranged to be moved independently of each other to different and opposite angles on opposite sides of two parallel planes, two contact devices on said predetermining mechanism for engaging the control portions on the pattern, for setting the guides in parallelism when the contact devices both engage control portions on the zero planes of the pattern and to vary the angles of said guides in accordance with the variations of the control portions on opposite sides of the zero planes, and means independent of the pattern for actuating said

contact devices in both directions, a fabric feeding device, and means movable over said guides for actuating the feeding device, substantially as described.

40. A feed control mechanism for an embroidery machine comprising a double faced pattern each face having control portions in different planes, the control portions on each face being on opposite sides of a zero plane, the two zero planes being parallel to each other, a feed predetermining mechanism having two guides for a fabric feed and arranged to be moved independently of each other, to different and opposite angles on opposite sides of two parallel planes, two contact devices on said predetermining mechanism for engaging the control portions on the pattern, for setting the guides in parallelism when the contact devices both engage control portion on the zero planes of the pattern and to vary the angles of said guides in accordance with the variations of the control portions on opposite sides of the zero planes, and means independent of the pattern for actuating said contact devices in both directions, a pair of oscillating pivots, a fabric feeding device carried by said pivots, and means moving over said guides for oscillating the pivots, substantially as described.

41. An embroidery machine having fabric feeding means, means for actuating the feeding means, a pattern, means for actuating the pattern, control means between the pattern and the feed actuating means, and means to actuate the control means independently of the pattern, substantially as described.

42. An embroidery machine having fabric feeding means, means for actuating the feeding means, a pattern, means for actuating the pattern in a continuous manner, control means between the pattern and the feed actuating means, and means to actuate the control means independently of the pattern, substantially as described.

43. An embroidery machine having fabric feeding means, means for actuating the feeding means, a pattern, means for actuating the pattern, control means co-acting with the pattern for determining the movement of the feed actuating means, and means independent of the pattern for setting the control means between each stitch of the embroidery machine.

44. An embroidery machine having fabric feeding means, means for actuating the feeding means, a pattern, means for actuating the pattern, control means between the pattern and the feed actuating means having spring actuated fingers co-acting with the pattern, and means to actuate the control means independently of the pattern, substantially as described.

45. Fabric feeding mechanism for an em-

brodering machine, comprising a movable pattern and a feed control mechanism controlled by the pattern, means for moving the pattern, and means for re-setting the feed control independently of the pattern moving means, substantially as described.

46. Pattern mechanism for controlling the feeding movement of a feeder for feeding fabric with relation to the needle of an embroidery machine, comprising a movable pattern strip having recesses and projections on opposite sides thereof, control mechanism between the pattern and the feeder on opposite sides of the pattern strip, and means for moving the control mechanism away from and toward the opposite sides of the pattern for each stitch, whereby a pattern having a relatively short movement can be used, substantially as described.

47. Pattern mechanism for controlling the feeding movement of a feeder for feeding fabric with relation to the needle of an embroidery machine, comprising a movable pattern strip having recesses and projections on opposite sides thereof, control mechanism comprising two pivoted members between the pattern and the feeder on opposite sides of the pattern strip, and means for moving the control mechanism away from and toward the opposite sides of the pattern for each stitch, whereby a pattern having a relatively short movement can be used, substantially as described.

48. Pattern mechanism for controlling the feeding movement of a feeder for feeding fabric with relation to the needle of an embroidery machine, comprising a movable pattern, means for moving the pattern in a continuous manner, control mechanism between the pattern and the feeder, and means for moving the control mechanism away from and toward the pattern for each stitch, whereby a pattern having a relatively short movement can be used, substantially as described.

49. Pattern mechanism for controlling the feeding movement of a feeder for feeding fabric with relation to the needle of an embroidery machine, comprising a movable pattern strip having recesses and projections on opposite sides thereof, control mechanism comprising two slides between the pattern and the feeder, one slide on each side of the pattern strip and means for moving the control mechanism away from and toward the opposite sides of the pattern for each stitch, whereby a pattern having a relatively short movement can be used, substantially as described.

50. Pattern mechanism for controlling the feeding movement of a feeder for feeding fabric with relation to the needle of an embroidery machine, comprising a movable pattern strip having recesses and projections on opposite sides thereof, control

mechanism comprising a slide on opposite sides of the pattern between the pattern and the feeder, and means for moving the control mechanism away from and toward the opposite sides of the pattern for each stitch, whereby a pattern having a relatively short movement can be used, substantially as described.

51. Pattern mechanism for an embroidery machine, comprising pattern controlled means for moving the fabric including oppositely disposed movable slides, a pattern for determining the movement of said slides in one direction, means for moving said slides away from the pattern, and spring means for moving the slides toward the pattern, substantially as described.

52. Pattern mechanism for an embroidery machine, comprising pattern controlled means for moving the fabric including oppositely disposed movable slides, a pattern for determining the movement of said slides in one direction, a spring finger on the end of each slide adapted to engage the pattern, and means for moving said slides, substantially as described.

53. An embroidering machine having a feeder for shifting the fabric to be embroidered relative to the machine needle, a power shaft, connections between the power shaft and needle for reciprocating the needle, a lever an adjustable fulcrum for the lever, a cam actuated by the power shaft for moving one end of the lever, a feeder shifting device connected to the other end of the lever, and a pattern controlled mechanism for controlling the movement transmitted from the shifting device to the feeder, substantially as described.

54. An embroidering machine having a feeder for shifting the fabric to be embroidered relative to the machine needle, a power shaft, connections between the power shaft and needle for reciprocating the needle, a lever, an adjustable fulcrum for the lever, a cam actuated by the driving shaft for moving one end of the lever, a feeder shifting device connected to the other end of the lever, and a pattern controlled mechanism for controlling the movement transmitted from the shifting device to the feeder, substantially as described.

55. An embroidering machine having a feeder for shifting the fabric to be embroidered relative to the machine needle, a power shaft, connections between the power shaft and needle for reciprocating the needle, a lever, an adjustable fulcrum for the lever arranged to permit the fulcrum to be adjusted in a plane extending through the longitudinal axis of the lever when at one extreme of its movement to vary the extent of its movement to the other extreme of its movement, a cam actuated by the driving shaft for moving one end of the lever, a

feeder shifting device connected to the other end of the lever, and a pattern controlled mechanism for controlling the movement transmitted from the shifting device to the feeder, substantially as described.

56. An embroidering machine having a feeder for shifting the fabric to be embroidered relative to the machine needle, a power shaft, connections between the power shaft and needle for reciprocating the needle, a pattern, means connected to the power shaft for moving the pattern, control devices co-acting with the pattern, means for actuating the control devices in one direction connected to the power shaft, means for moving the control devices in the other direction, feeder actuating means connected to the power shaft, and connections between the feeder actuating means and control devices controlled by the control devices for determining the movement of the feeder by the feeder actuating mechanism, substantially as described.

57. An embroidering machine having a feeder for shifting the fabric to be embroidered relative to the machine needle, a power shaft, connections between the power shaft and needle for reciprocating the needle, a pattern, means connected to the power shaft for moving the pattern, control devices co-acting with the pattern, means for actuating the control devices in one direction connected to the power shaft, spring means for moving the control devices in the other direction, feeder actuating means connected to the power shaft, and connections between the feeder actuating means and control devices controlled by the control devices for determining the movement of the feeder by the feeder actuating mechanism, substantially as described.

58. An embroidering machine having a feeder for shifting the fabric to be embroidered relative to the machine needle, a power shaft, connections between the power shaft and needle for reciprocating the needle, a pattern, means for moving the pattern, feelers co-acting with the pattern, means for moving the feelers relative to the pattern, feeder actuating means, and control means between the feeder actuating means and the feelers for controlling the movement of the feeder by the actuating means, substantially as described.

59. An embroidering machine having a feeder for shifting the fabric to be embroidered relative to the machine needle, brake means for the feeding means, a power shaft, connections between the power shaft and the needle for reciprocating the needle, a pattern, means connected to the power shaft for moving the pattern, control devices co-acting with the pattern, means for actuating the control devices in one direction connected to the power shaft, means for

- moving the control devices in the other direction, feeder actuating means connected to the power shaft, and connections between the feeder actuating means and control devices controlled by the control devices for determining the movement of the feeder by the feeder actuating mechanism, substantially as described. 50
- 5 60. An embroidering machine having fabric feeding means including gearing, and resilient means for preventing back lash of the gearing directly connected to the feeding means whereby a predetermined feed is obtained, substantially as described. 55
- 10 61. An embroidering machine having a fabric feeding member, two sets of lever mechanisms for moving the feeding member, a train of gears for actuating each lever mechanism, pattern mechanism for controlling movement of the gear trains, and resilient means connected to each gear train for preventing back lash whereby a predetermined feed is obtained, substantially as described. 60
- 15 62. A pattern controlled fabric feeding mechanism for an embroidering machine having a lever with a fulcrum between its ends for moving the fabric feeder, means for moving the lever, and a floating support for the lever for causing one end of the lever to move in a straight line, substantially as described. 65
- 20 63. A pattern controlled fabric feeding mechanism for an embroidering machine having a lever with a fulcrum between its ends for moving the fabric feeder, means for moving the lever, a floating support for the lever for causing one end of the lever to move in a straight line, and adjustable means for shifting the fulcrum of said lever for varying the movement of one end of the lever, substantially as described. 70
- 25 64. A pattern controlled fabric feeding mechanism for an embroidering machine having a reciprocating needle, a driving shaft for reciprocating the needle, a lever fulcrumed between its ends included in the fabric feeding mechanism, a cam on the driving shaft for moving and one end of the lever a fixed distance for each reciprocation of the needle, and adjustable means for shifting the fulcrum of the lever to vary the throw of the other end of the lever and vary the feed of the fabric, substantially as described. 75
- 30 65. An embroidering machine having a fabric feeding tambour, a lever fixedly connected to the tambour, a shaft, a lever connected to said shaft, a second shaft having a lever connected thereto, a link pivotally connected to the last lever and the tambour, and pattern controlled means for oscillating said shafts, substantially as described. 80
- 35 66. An embroidering machine having a fabric feeding tambour, a lever fixedly connected to the tambour, a shaft, a lever connected to said shaft, a second shaft having a lever connected thereto, a link pivotally connected to the last lever and the tambour, pattern controlled means for oscillating said shafts, and braking means for said shafts, substantially as described. 85
- 40 67. An embroidering machine having a fabric feeding means, a pair of pivots, levers connected to said pivots and the feeding means, a gear train connected to each pivot, and pattern controlled means for actuating the gear trains independently of each other, substantially as described. 90
- 45 68. An embroidering machine having a fabric feeding means, a pair of pivots, levers connected to said pivots and the feeding means, a gear train connected to each pivot, pattern controlled means for actuating the gear trains independently of each other, and braking means for each gear train, substantially as described. 95
69. An embroidering machine having fabric feeding means, a pair of pivots, levers connected to said pivots and the feeding means, a gear train connected to each pivot, spring means in each train for preventing back lash, and pattern controlled means for actuating the gear trains independently of each other, substantially as described. 96

In testimony whereof I have hereunto set my hand.

LEON SCHWARZMANN.
